RACK ADAPTER

Lester Dubin, Pelham Manor, Maury Paulson, Huntington, and Benjamin Shmurak, Lynbrook, N.Y., assignors to Lambda Electronics Corporation, Huntington, N.Y., a corporation of New York

Filed Mar. 23, 1965, Ser. No. 84,417

Term of patent 14 years

(Cl. D26—5)

The figure is an isometric view of a rack adapter, showing our new design wherein the left and right sides are substantial mirror images of one another and the rear and bottom are substantially plain and unornamental.

We claim:

The ornamental design for a rack adapter, as shown and described.
